(57) **CLAIM**

The ornamental design for a silicone pad as shown and described.

DESCRIPTION

FIG. 1 is a top, front and right side perspective view of a silicone pad showing our new design;

FIG. 2 is a bottom, rear and left side perspective view thereof;

FIG. 3 is a front elevation view thereof;

FIG. 4 is a rear elevation view thereof;

FIG. 5 is an enlarged left side elevation view thereof, provided for clarity of illustration;

FIG. 6 is an enlarged right side elevation view thereof, provided for clarity of illustration;

FIG. 7 is an enlarged top plan view thereof, provided for clarity of illustration; and,

FIG. 8 is an enlarged bottom plan view thereof, provided for clarity of illustration.

The broken lines in the drawings illustrate portions of the silicone pad that form no part of the claimed design.

1 Claim, 6 Drawing Sheets
